2 Sheets-Sheet 2

UNITED STATES PATENT OFFICE.

HUGH E. MONTGOMERY, OF CHICAGO, ILLINOIS.

AUTOMOBILE SPOTLIGHT.

Application filed March 31, 1924. Serial No. 703,203.

To all whom it may concern:

Be it known that I, HUGH E. MONTGOMERY, a citizen of the United States, and resident of Chicago, in the county of Cook and State of Illinois, have invented certain new and useful Improvements in Automobile Spotlights, of which the following is a specification.

My invention relates to improvements in spot lights and it consists of the constructions, combinations and arrangements herein described and claimed.

An object of the invention is to provide a spot light which is operated by the turning of a handle to throw a beam along a vertical or a horizontal plane.

A further object of the invention is to provide a spot light which can be rotated horizontally and tilted vertically by the use of only one shaft extending through the car body.

Other objects and advantages will appear in the following specification, reference being had to the accompanying drawings, in which—

Figure 1 is a perspective view of the improved spot light.

Figure 2 is a vertical section taken on the line 2—2 of Figure 1.

Figure 3 is a horizontal section of the spotlight taken on the line 3—3 of Figure 2.

Figure 4 is a vertical horizontal section taken substantially on the line 4—4 of Figure 2.

Figure 5 is a detail perspective view of the fixed horizontal standard.

Figure 6 is a plan view of the movable clutch.

Figure 7 is a section on the line 7—7 of Figure 6, the details of the clutch being well illustrated.

Figure 8 is a detail section on the line 8—8 of Figure 4, showing how the straight teeth of the shaft pinion are slidably in mesh with the tapering teeth of the ring gear.

Figure 9 is a front elevation of the movable lamp standard.

Figure 10 is a section of said standard on the line 10—10 of Figure 9.

Figure 11 is a detail section of the electric current switch inside of the fixed standard.

Figure 12 is a detail section of the adjustable ball bearing of the lamp head.

In carrying out the invention provision

is made of a tubular standard 1, preferably cylindrical, which has a flange 2, circular or otherwise, provided with a suitable number of holes 3 through which screws 4 are driven to fasten it in a horizontal position on the outside of a motor vehicle. The wall W is intended to represent a part of the motor vehicle, whether this be of wood or metal. It is easily conceivable that this flange may be mounted upon the lower front glass, means other than screws being then used. A circular enlargement 5 at the free extremity of the standard 1 provides a head against which a somewhat corresponding head 6 of the movable lamp standard 7 is revoluble when the lamp 8 is rocked in the vertical plane. The standard 1 is cut away at 9 at the place where the head 5 occurs providing a recess of a depth approximately one-half the diameter of the standard. This recess is occupied by the head of the movable standard, the arrangement being such that there is a close joint all around as is obviously necessary.

A spring 10 keeps the edge of the movable head 6 tight against the edge of the fixed head 5. This spring is disposed upon a stud 11 which is suitably fixed at the base of the head 5 and projects outward therefrom (Fig. 5). The head 6 turns upon the stud. The extremity is threaded, and when the nut 12 is screwed in place the cup 13 is pressed against the spring 10. The resulting tension of the spring acts against the wall 14 of the receptacle 15 and ultimately presses the edge of the movable head 6 against the head 5 as already stated. The receptacle 15 is a part of the movable head as can readily be seen (Figs. 2 and 3). A thimble 16, screwed into the end of the receptacle 15, both conceals the nut 12 and holds it in position upon the stud. There is not room enough between the nut and the thimble to permit the nut to work off. A spring 17 on the base of the receptacle 15 presses against a clutch 18 to normally keep the teeth 19 in locked engagement with the teeth 20 of a ring gear 21. The ring gear is circular as its name implies. It has teeth on both sides of the ring portion. The teeth 20 are the clutch teeth. The teeth 22 on the opposite side are those by means of which the ring gear is turned by the meshing teeth 23 of the operating shaft 24. The ring gear includes a circular flange 25.

This circular flange has bearing in a cir-

circular groove or recess 26 formed by a rabbet around the inner edge of the movable head 6. This groove or rabbet provides the bearing for the ring gear. The spring 10 presses 5 the movable head toward the circular flange of the gear, but by properly machining the parts there will be sufficient clearance to prevent such binding upon the gear as will make turning difficult. The turning is done 10 by the pinion 23. When the clutch 18 is in engagement with the ring gear, as it normally is, a turning of the shaft 24 will cause a corresponding turning of the clutch, the circular head 6, the standard 7 and the 15 lamp 8. This turning will be in the plane of the axis of the standard 1, in other words, an up and down motion of the lamp 8.

Bodily turning of the head 6 with the clutch 18 is produced by keys 27 (Figs. 2, 9 20 and 10) with which the clutch has slide engagement in grooves 28 (Figs. 2 and 6).

However, when the clutch 18 is disengaged from the ring gear 21, a turning of the shaft 24 will result in a turning of the ring gear 25 only, and this in turn revolves the lamp 8 in the horizontal plane.

Disengagement of the clutch 18 from the clutch teeth 20 of the ring gear is effected by pushing the operating shaft 24 outward 30 in the direction of the arrow A (Fig. 3). The tip of the shaft is tapered at 29. The upper and confronting portion of the clutch is beveled at 30. When the surfaces mentioned meet upon pushing the shaft outward 35 as stated, the result is a displacement of the clutch 18 to the right upon the receptacle 15 (Figs. 2 and 3) against the tension of the spring 17. This position of the clutch is maintained as long as there is pressure on 40 the shaft 24, and obviously the clutch teeth 19 and 20 remain disengaged so that the ring gear may be turned freely.

At this point it is to be noted that the displacement of the clutch 18 takes place 45 in respect to the ring gear 21. The ring gear is maintained in position by the engagement of the flange 25 with the groove 26. This engagement is described as the bearing for the ring gear, but additional bearing for the ring gear is provided by its 50 mounting upon the hub 31 of the clutch. The bevel 30 is formed upon a reduced prominence 32 at one side of the hub (Figs. 3 and 7).

Now as to the turning of the lamp in the horizontal plane: A shaft 33 in the movable standard 7 (Fig. 2) carries a pinion 34 which meshes with the ring gear 21. Inasmuch as the pinion 34 engages on the 60 same side of the ring gear 21 that is engaged by the clutch 18 it becomes necessary to cut the clutch away at 35 (Fig. 6) to provide a chamber in which the pinion turns. It must be remembered that the clutch 18 does not 65 revolve; it merely slides back and forth on

the keys 27 and the chamber 35 is always in the same relative position in respect to the pinion 34. It must also be borne in mind that Figure 3 is taken at right angles to Figure 2 and for that reason the pinion 34 70 does not show, it being in a plane above.

The pinion 34 is hollow to provide a chamber 36, properly known as a contact chamber inasmuch as it is occupied by the fixed electrical contact 37 and the movable 75 electrical contact 38. The latter is carried by a boss 39 formed on that side of the clutch 18 where the chamber 35 occurs (Fig. 6). The boss is necessarily smaller than the chamber 36 to permit the limited movement 80 of the clutch 18 when sliding it from engagement with the ring gear teeth 20. This sliding of the clutch is not sufficient to disengage the contacts 37 and 38, these always remaining in engagement and rubbing 85 against each other when the lamp is being rotated.

Current is supplied to the incandescent bulb 40 from the usual source carried by the automobile (not shown) by means of a wire 90 41 which runs to the movable contact 42 of a switch 43 (Fig. 11) inside of the fixed standard 1. The contact 42 engages a fixed contact 44 upon depression of the switch button 45 (Figs. 1 and 4), whereupon one side of the lighting circuit is closed so that current may flow through the wire 45 which has electrical connection with a brush 46 inside of the head 5 (Figs. 4 and 5). This brush bears against an insulated collector ring 47 which is connected with the contact 38 (Figs. 2 and 7) by means of a wire 48 concealed inside of the movable clutch 18. The wire 48 is threaded through suitable bores substantially as shown in Figure 7.

The wires 41 and 45 are positive. The current from the bulb 40 has a grounded return as is customary in all automobile lighting practice. A wire 49 leads from the contact 37 to the bulb.

The shaft 33 has a bore through which the wire 49 passes. A cone 50 on the shaft 33 engages the balls 51 in the bearing sleeve 52. This sleeve has an ample V-shaped groove 65 the straight walls of which, particularly the upper wall (Fig. 12) being of a slightly greater inclined angle than that of the cone 50. The sleeve 52 is suitably fixed inside of the movable standard 7, the shaft 33 being held in the central position by the wedging action of the balls between the ball races. These provide a perfect fit both radially and axially when the inverted cup is seated on the gear housing. The shaft carries the inverted cup 54, referred to. The edge of this cup bears on the rim of the standard 7 and thus provides a support for the lamp structure above. This cup is held in place on the shaft as shown. Several pins 66, carried by the inverted cup, engage 120 125 130

the floating ball retaining ring 67 and are held in such engagement by nuts 55 and 68, the latter being a jam nut. Both are screwed upon the threaded end of the shaft.

- 5 A knob or handle 56 on the end of the operating shaft 24 provides for both pushing and turning the shaft. The shaft is turned when it is desired to rock the spot light 8 vertically; it is merely pushed outward and then turned when it is desired to move it horizontally. The inner end of the operating shaft 24 is fixed to the knob 56 by means of a cap 57 which, when screwed in place, so contracts upon the end 10 of the shaft that the parts are clamped in position (Fig. 4). The knob 56 has a hollow hub 59 which is deep enough to permit the necessary motion of the knob in respect to a fixed sleeve 60 when the operating shaft 24 is pushed outward.

15 This sleeve is screwed into the flange 2 and is thus held in a rigid position. The shaft 24 works inside of the sleeve. The sleeve carries a small plate 61 in which the 20 rod of the switch button 45 has bearing. This plate is clamped upon the sleeve 60 by means of a bushing 62 and a circular nut 63 which is screwed thereupon.

30 *The operation.*

Turning the knob 56 causes the spotlight 8 to rock in the vertical plane. A turn of the knob to the right (assuming the operator to be facing the knob in Figure 1) causes the light 8 to incline downward; a turn to the left causes the lamp to incline upward. Rapid right and left turning causes the lamp to reciprocate.

40 If the operator first pushes outward on the knob 56 and then turns the same to the right, the spotlight 8 will swing toward the left in the horizontal plane. Conversely, a left turn of the knob 56 will swing the lamp to the right.

45 Consider these two actions separately. The outer end of the operating shaft 24 terminates in a spur pinion 23 and a tapered end 29. The spur pinion constantly meshes with the teeth 22 of a ring gear 21. This gear has similar teeth 20 on the opposite side (Figs. 2 and 3), and with these a clutch 18 has normal engagement by virtue of the pressure of a spring 17 at the opposite end of the clutch. The clutch can slide but not turn, the engagement of grooves 28 with relatively fixed keys 27 making provision for the former action. It is easy to understand that when the non-turnable clutch 18 engages the ring gear 21 so that it cannot turn, and a turning movement is imparted to the ring gear by the spur pinion 23, something must yield. It is the movable standard 7 that yields; the entire ring gear 21, clutch 18 and head 6 then turning upon the fixed stud 11 as described at the be-

ginning of this subject. Consider now the second action: Upon pushing outward on the knob 56 the tapered end 29 of the operating shaft will meet the bevel 30 of the clutch and cause the lateral displacement 70 of the clutch so that the clutch teeth 19 and 20 are disengaged. Subsequent turning of the pinion 23 causes a turning of the ring gear independently of the clutch, and this turning is transmitted to the lamp 8 75 by way of the lamp pinion 34 which meshes with the ring gear 21 at a place 35 in clutch 18 where the adjacent part of the clutch 18 is cut away.

80 The teeth 22 and 20 of the ring gear are of the familiar tapering formation. The problem of sliding the pinion 23 in respect to the teeth presents itself, but is overcome by the arrangement illustrated in Figure 3. The sides of the teeth in the pinion 23 are 85 substantially straight and of a thickness no greater than the narrowest width of the spaces between the teeth of the gear 22. The reader can readily see that with such an arrangement the pinion 23 is readily slid 90 back and forth without jamming in the gear 22.

95 A point to bear in mind in connection with the sliding of the pinion 23 is this: It is not necessary for the operator to continue outward pressure on the knob 56 when he desires to turn the lamp 8 horizontally. The pressure of the spring 17 is at right angles to the axis of the operating shaft 24, the result being a lateral pressure on the tapered end 29 when the clutch 18 is in place and a tendency to hold the shaft in the extended position. The angles of the tapered end 29 and of the bevels 30 are hardly abrupt enough to force the shaft 24 back to 105 position under the tension of the spring 17.

110 In reference to the ball bearing of the lamp head: This bearing is adjustable as will readily be seen in Figure 12. Screwing down on the nut 55 fixes the bearing balls in the proper position in reference to the sleeve 52 and cone 50. The ball bearing illustrated is well adapted to keep the shaft or spindle 33 in the desired central position. The sleeve 52 is permanently 115 fixed within the standard 7. The lamp 8 is soldered or otherwise secured upon the cup 54. The shaft 33 has a non-rotational fitting in the cup 54, for which purpose the upper end of the shaft may be made non-circular. Preferably the cup 54 and shaft 33 are made in one piece. Thus, parts 7 and 52 are integral and parts 54 and 8 are also integral with shaft 33. The holding together of the various parts depends 120 upon the balls 51. The ball retainer ring 67 is held down by a number of pins 66 so that the bearing balls 51 normally occupy substantially the lowermost part of the 125 downwardly converging ball race. Upon 130

unscrewing the nuts 55 and 68 the ring 67 is allowed freedom to move upwardly so that the balls 51 pass inwardly to the smaller part of the ball race. The pins 66 are 5 pulled out flush with the inside of the cup 54 thereby sufficiently loosening the ring 67 so that the balls may pass beyond the upper and inner ridge of the groove 65 and the various parts concerned may be disassembled. 10 The particular combination shown is very easy to assemble and adjust, as well as to manufacture in practice inasmuch as there are no parts which require great accuracy. As stated before, the wedge action of the 15 balls between the two ball races provides a perfect fit both radially and axially when the inverted cut is once seated on the gear housing.

While the construction and arrangement 20 of the improved automobile spotlight as herein described and claimed is that of a generally preferred form, obviously modifications and changes may be made without departing from the spirit of the invention 25 or the scope of the appended claims.

I claim:-

1. A spotlight comprising a lamp, a standard by which it is carried, a fixed standard upon which the lamp standard 30 is movably mounted, a single operating shaft, a lamp shaft having a pinion, a ring having a gear with which it constantly meshes, a clutch engageable with the same gear teeth to keep the gear from 35 turning, a second gear on said ring engaged by a pinion on the operating shaft, means by which the clutch is keyed to the movable standard causing a rocking of the standard and lamp in one plane upon mere turning 40 of the operating shaft, and means by which the clutch is displaced to disengage the first teeth upon pushing the operating shaft, subsequent turning of the shaft revolving the lamp independently on the movable standard through the ring and first mentioned pinion.

2. A spotlight comprising a lamp, a movable standard upon which the lamp is movably mounted, a fixed standard by which the movable standard is carried, a double gear-faced ring, an operating shaft having a pinion in mesh with one of the gear faces, a 50 slideable clutch keyed to the movable member and engaging the other gear face causing the movable member to rock when the operating shaft is turned, a lamp shaft having a pinion meshing with the clutch gear face, and associated means on the operating shaft and the clutch for causing disengagement of the clutch upon swinging the shaft and a turning of the lamp upon the movable standard upon subsequent turning of the operating shaft.

3. A spotlight comprising a lamp, a 55 standard upon which the lamp is movably

mounted, a fixed standard by which said standard is movably carried, a double-faced ring gear having a circular flange engaging parts of both standards to retain the ring, a clutch slidably keyed on the movable standard, engaging one gear and having a hub upon which the ring has bearing; an operating shaft having a pinion meshing with the other gear bodily rocking the movable standard and lamp upon turning said shaft while the clutch is in engagement, a lamp shaft having a pinion meshing with the clutch gear, and associated means on the operating shaft and clutch causing a disengagement of the clutch upon an axial 70 movement of the shaft, a subsequent turning of the operating shaft rotating the ring gear, lamp shaft pinion and lamp.

4. A spotlight comprising a lamp, a standard upon which it is movably mounted, 85 said standard having a rabbeted edge, a fixed standard having a portion presenting an edge confronted by said rabbet when the standards are fitted together, a double-gear faced ring having a circular flange occupying said rabbet to retain the ring in position, a slideable clutch, keys on the movable standard on which the clutch is slideable, means to engage the clutch with one of the gear faces, an operating shaft having a 90 pinion meshing with the other gear face causing a rocking of the movable standard and lamp upon turning the operating shaft while said clutch is in engagement, the lamp shaft having a pinion meshing with said clutch gear, and associated means on the operating shaft and clutch, said means including tapered and beveled portions respectively, for laterally displacing the clutch against the tension of said means upon an 100 axial movement of the operating shaft permitting independent rotation of the ring, lamp pinion and lamp.

5. A spotlight comprising a lamp, a standard upon which it is movably mounted, a 110 fixed standard movably carrying the lamp standard, means on the movable standard forming a receptacle having an end wall, means including a stud carried by the fixed standard extending through said wall which thus bears thereon, a double gear-faced ring, a clutch bearing on the receptacle having a hub on which the ring is journalled and including a prominence having bearing on the stud, means including a spring disposed about the receptacle pressing the clutch into contact with the nearest gear face, means on the movable standard on which the clutch is slidably keyed, an operating shaft having a pinion in mesh with the other gear face 115 causing a bodily rocking of the movable standard upon turning the shaft, a lamp shaft having a pinion meshing with the clutch gear, and associated means on the shaft and prominence including tapered and 120 beveled portions respectively, for laterally displacing the clutch against the tension of said means upon an axial movement of the operating shaft permitting independent rotation of the ring, lamp pinion and lamp.

125 130

beveled portions for laterally displacing the clutch upon axial movement of the shaft, subsequent turning of the shaft revolving the lamp independently of the movable standard.

6. The subcombination in a spotlight of a lamp, a grounded electric bulb in the lamp, a shaft by which the lamp is turned, a hollow pinion carried by the shaft, a ring having a gear with which the pinion meshes, a 10 slideable but non-rotatable clutch engageable with said gear to prevent the ring and pinion from turning, means to slide the clutch and thus free the ring, and electrical connections for said bulb, including a conductor passing through the clutch, a boss carried by the clutch occupying the hollow pinion but being smaller than the hollow part to permit the movement of the clutch, a contact on said boss at which said conductor terminates, and a wire leading from the bulb through the shaft to a companion contact with which the other has permanent but movable engagement.

25 7. The subcombination in a spotlight comprising a lamp having a grounded electric bulb, a slideable clutch having a collector ring, a brush representing the terminal of an electric circuit engaging the ring in all 30 positions of the clutch, a boss on the clutch carrying a contact which has electrical connection with said ring, a shaft by which the lamp is turned having a pinion containing a chamber occupied by said boss, said boss 35 being smaller than the chamber to permit sliding movement of the clutch, and a contact carried by the pinion in said chamber in electrical connection with the bulb, said contacts being large enough to remain in engagement at each position of the clutch.

40 8. The subcombination in a spotlight comprising a ring having a clutch gear, a circular flange on the ring, a slideable clutch having a hub upon which the ring has bearing, 45 means to press the clutch into engagement with said gear, means to reversely move the clutch against the tension of said means to release the ring, fixed and movable standards between which the ring is held in position by means of said circular flange, and a lamp carried by the movable standard adapted to be actuated through said movable standard according to the positions of said clutch.

55 9. The subcombination in a spotlight of a fixed standard having a stud, a lamp, a movable standard carrying the lamp and being turnable on the stud, keys formed on part of the standard, a clutch slideable on the stud 60 and being engageable with said keys, a ring having gears on opposite faces one of which is engaged by the clutch, an operating shaft having a pinion meshing with the other gear and causing bodily turning of the movable standard by virtue of said clutch,

a tapered end on the shaft, and a beveled prominence on the clutch by which the clutch is displaced upon axial shifting of the shaft, said pinion being slideable over the last gear without disengagement.

70 10. The subcombination in a spotlight of a fixed standard having a stud, a movable standard turnable on the stud, a clutch slideable on the stud and engaging keys in the movable standard, a ring having gears on opposite faces one of which is engaged by the clutch, an operating shaft having a pinion meshing with the other gear and causing bodily turning of the movable standard by virtue of said clutch, a tapered end on the shaft, and a beveled prominence on the clutch by which the clutch is displaced upon axial shifting of the shaft, said pinion being slideable over the last gear without disengagement, and a lamp shaft having a pinion in engagement with the ring gear which is then rotatable upon subsequent turning of the operating shaft.

75 11. The subcombination in a spotlight of a lamp standard, a lamp revolvably mounted thereon, a ring having two gear faces, a pinion meshing with one gear, an operating shaft having a pinion meshing with the other gear, a clutch engaging the first gear causing the standard and lamp to rock in one plane upon turning of the operating shaft, means associated with the shaft and clutch for disengaging the latter upon axial movement of the shaft to cause revolving of the lamp in another plane upon turning of the shaft, and fixed means to limit the axial movement of the shaft including a fixed sleeve, and a bushing on the shaft.

80 12. The subcombination in a spotlight of a fixed standard carrying a stud, a lamp, a movable standard carrying the lamp and having means constituting a receptacle having a wall at one end through which the stud passes and open at the other end, a cup fitted upon the stud, a spring situated between the cup and said wall pressing against said wall and keeping the movable standard seated against the fixed standard, means on the end of the stud abutted by the cup, and means fitted in the open end of the receptacle concealing said means.

85 13. The subcombination in a spotlight of a tubular fixed standard terminating in a circular head and having a portion cut away to provide a recess, a movable lamp standard having a circular hollow head occupying said recess the edges of the two heads abutting, a stud mounted in the fixed head, means on the movable head constituting a receptacle receiving the end of the stud and having a wall bearing thereon, a cup mounted on the stud and fitting inside of the receptacle, means on the end of the stud against which the cup abuts, a spring situated in the space between the cup and stud

- pressing against the wall to keep said edges in contact, and means fitted inside of the receptacle also abutted by the cup and concealing the aforesaid means.
- 5 14. The subcombination in a spotlight of a lamp standard, a bearing sleeve carried thereby, a lamp having an inverted cup support fitted down upon the sleeve, a shaft carried by the support and having a bearing cone, bearing means including balls situated between the cone and bearing sleeve, said sleeve having a bearing surface situated at an angle different from that of the cone, means carried by the cup extending into engagement with a retaining ring of the balls, means carried by the shaft engaging said last means to permit adjustment of the balls, and means carried by the shaft including a pinion by which it and the lamp are turned.
- 10 15. In a spotlight, a single operating shaft having a pinion at the end, a ring having gears on opposite faces of which one meshes with the pinion for turning of the ring, a clutch having a portion projecting through the ring into the path of the operating shaft and including teeth engaging the other gear, a lamp, means by which the lamp is turned including a pinion meshing with said other gear, means upon which said clutch is
- 15 mounted to move at right angles to the operating shaft to either grip or release the ring, means including a spring keeping the clutch in normal engagement with the ring for turning of the clutch with the ring, and
- 20 30 35 means associated with both the shaft and clutch including tapered and beveled por-
- tions causing a displacement of the clutch and release of the ring upon axial movement of the shaft, said portions being at such angles that the spring tension will hold the clutch and shaft in position and the clutch in disengagement until the shaft is returned.
16. In a spotlight a lamp standard having a key, a turnable ring having a gear face, a lamp shaft having a pinion meshing with said gear face, a clutch slid in one direction upon the key to engage the gear face and normally prevent turning of the ring, said clutch being cut away providing a chamber to receive the pinion, and a rotatable and shiftable operating shaft to turn said ring, first being shiftable to slide the clutch in the other direction to release the gear face.
- 25 17. In a spotlight an operating shaft, a movable standard carrying a lamp, a double gear-faced ring, a spur pinion on the operating shaft meshing with one gear face of said ring to turn the ring, the teeth of the pinion being straight and fitting the narrowest spaces between said gear teeth to permit axial sliding of the operating shaft, clutch means engaging the other gear face causing rocking of the standard upon simply turning the operating shaft and ring, and lamp operating means also engaging said other gear face causing turning of the standard upon first sliding the operating shaft to displace the clutch means then turning the operating shaft.
- 30 35 65

HUGH E. MONTGOMERY.
